UNITED STATES PATENT OFFICE.

GEORGE WELLS, OF MONTREAL, QUEBEC, CANADA, ASSIGNOR TO HIMSELF AND C. H. SOLOMON & CO., OF SAME PLACE.

IMPROVEMENT IN WATER-ENGINES.

Specification forming part of Letters Patent No. 182,003, dated September 5, 1876; application filed June 6, 1876.

To all whom it may concern:

Be it known that I, GEORGE WELLS, of Montreal, in the Province of Quebec and Dominion of Canada, have invented a new and Improved Water-Engine, of which the following is a specification:

The invention will first be described in connection with drawing, and then pointed out in the claims.

Figure 1 is a sectional elevation of my improved engine, taken on the line *xx* of Fig. 2. Fig. 2 is a horizontal section on line *zz*, Fig. 1.

Similar letters of reference indicate corresponding parts.

A is the cylinder, which is mounted in bearings *C* of a case, *D*, on trunnions *B*, and has a circular valve, *E*, formed on the lower end, with one port, *F*, and fitted to the correspondingly-shaped valve-seat *G*, in which is the inlet *H* and the exhaust *I*, also the exhaust *J*, for the waste from the interior of case *D*.

K represents passages cored out in the cylinder, from the upper end down to the interior of the waste-water case, to conduct any water

leaking past the piston *L* into the case, to be discharged through the exhaust. A cap, *M*, screws onto the top of the cylinder, for a guide to the piston-rod *N*, and these passages *K* enter the cylinder, above the piston, under this cover.

The machine is also useful as a pump.

Having thus described my invention, I claim as new and desire to secure by Letters Patent—

1. The combination of waste-water case *D*, having exhaust *J*, with the oscillating cylinder *A*, substantially as specified.

2. Cylinder *A*, having passages *K* cored out from the upper end and opening into case *D*, substantially as specified.

GEORGE WELLS.

Witnesses:

O'HARA BAYNES,

Of the city of Montreal, Notary Public.

JOHN C. GRIFFIN,

Of the same place, Justice of the Peace and Notary Public.
